United States Patent Office

Des. 192,673
Patented Apr. 24, 1962

192,673

LIPSTICK

Victor Silson, New York, N.Y., assignor to Helena Rubinstein Inc., New York, N.Y., a corporation of New York

Filed May 5, 1959, Ser. No. 55,781

Term of patent 14 years

(Cl. D86—10)

FIG. 1 is a front elevational view of a lipstick showing my new design;

FIG. 2 is a side elevational view thereof;

FIG. 3 is a rear elevational view; and

FIG. 4 is a top plan view.

The essential features of the design reside in the portions shown in solid lines on the drawing.

I claim:

The ornamental design for a lipstick, as shown and described.
